DESIGN FOR A DISPLAY RACK FOR ROLLED FLEXIBLE FLOOR COVERINGS OR THE LIKE

William J. Ferris, Arlington, N. J., assignor to
Congoleum-Nairn Inc., a corporation of New
York

Application December 3, 1946, Serial No. 135,231

Term of patent 14 years

(Cl. D80—9)

To all whom it may concern:

Be it known that I, William J. Ferris, a citizen of the United States of America and residing in Arlington, in the county of Hudson and State of New Jersey, have invented a new, original, and ornamental Design for a Display Rack for Rolled Flexible Floor Coverings or the like, of which the following is a specification, reference being had to the accompanying drawing, forming a part thereof, in which Fig. 1 is a front, perspective view of a display rack for rolled flexible floor coverings or the like, showing my new design, and Fig. 2 is an end elevation thereof, the back being plain.

I claim:

The ornamental design for a display rack for

rolled flexible floor coverings or the like, substantially as shown and described.

WILLIAM J. FERRIS.
